UNITED STATES PATENT OFFICE.

CARL J. A. SJOBERG, OF BROOKLYN, NEW YORK, ASSIGNOR TO THE GARVIN MACHINE COMPANY, OF NEW YORK.

TYPE-WRITING MACHINE.

SPECIFICATION forming part of Letters Patent No. 445,128, dated January 20, 1891.

Application filed January 27, 1890. Serial No. 338,197. (No model.)

To all whom it may concern:

Be it known that I, CARL J. A. SJOBERG, a citizen of the United States, residing at Brooklyn, Kings county, New York, have invented 5 certain new and useful Improvements in Type-Writing Machines, fully described and represented in the following specification and the accompanying drawings, forming a part of the same.

- 10 This invention relates to certain improvements in a type-writing machine having a rotary type-wheel, and also having a feed-roll mounted upon a vibrating frame and oscillated to and from the type-wheel with the paper. In such machine the feed-roll is pivoted upon a carriage arranged to slide longitudinally upon the vibrating frame; and the improvements consist partly in an annular ribbon inclosing the periphery of the type-wheel, 15 partly in the combination, with the movable carriage, of feeder-guides adapted to hold the paper against a single feeder-roll, partly in a stationary bell with a hammer suspended by a lever-arm and a tappet upon the vibrating carriage to strike the lever-arm near its fulcrum, partly in a ribbon-guard affixed to the vibrating carriage, and partly in an improved means of forming and setting an electrotype-plate upon the type-wheel.
- 20 In the annexed drawings, Figure 1 is a plan of the machine containing these improvements. Fig. 2 is a front elevation of the same in section on line $\alpha\alpha$ in Fig. 1, with the type-wheel, the ribbon, and its carrier removed to expose the parts behind them. Fig. 3 is an end elevation, partly in section, where hatched, on line yy in Fig. 1. Fig. 4 is an elevation of the type-wheel and spindle with the lettered strip removed. Fig. 5 is a vertical section of the type-wheel with the annular ribbon and its carrier. Fig. 6 is a vertical section of the annular ribbon fastened to its hoops. Fig. 7 is a plan of the ribbon and hoops. Fig. 8 is an edge view, and Fig. 9 a plan of the circular carrier, with dotted lines in Fig. 9 indicating an alternative construction. Fig. 10 is a view, broken for want of room, of the lettered strip adapted to fit a groove in the type-wheel. Fig. 11 represents

the inner or dished side of the blank for the lettered strip. Fig. 12 is a longitudinal section, and Fig. 13 a transverse section, of such blank. Fig. 14 is a section of the feed-carriage and feed-roll with the stationary feeder-guide. Fig. 15 is a section of the feeder-carriage and feed-roll with the movable feeder-guide; and Fig. 16 is a transverse section of the blank for the lettered strip, with a punch and die to cut the same to the desired width.

A is a wooden base; B, the iron bed of the machine; C, the type-wheel; D, its spindle, and E the bearing for the same.

f are bearings for the vibrating frame g , which is provided at its middle with a carriage-guide a , having a nearly vertical slot to admit the movable feeder-carriage b . Carriage-guides a' are also provided near the ends of the frame g .

The feed-roll d is mounted in bearings c upon the carriage and provided with notched wheel d' , having a spring d'' applied thereto to space the writing when the roll is turned by hand-wheel d^3 .

The carriage is provided, as heretofore, with a long slot b' , which passes through the central guide a , where it would be intersected by a pin to hold the carriage down movably upon the frame g .

The type-wheel C has flanges h at its margin, forming a cylindrical groove h' , (shown in Fig. 4,) and the type are formed upon an electrotype-strip s , (shown in Fig. 10,) which is made of suitable length and width to encircle the wheel in the groove h' . To trim the sides and ends of such strip to fit the groove accurately, the strip is preferably made in the electrotype-mold larger than the finished size, and to set such strip accurately in a die it is provided with a bent flange s' around its margin, by means of which it is accurately set in a recessed die S . (Shown in Fig. 14.) When thus set and the die fitted in a suitable punching-machine, a punch T is applied to the die and the strip cut to the proper length and width, as shown in Fig. 10, to fit snugly in the groove h' .

As shown in Figs. 1, 3, and 5, the ribbon r is shown of annular form suspended around the

type-wheel at a little distance from the type-faces, and thus obscures the wheel from view in Figs. 1 and 3 by wholly inclosing the same.

The ribbon is secured by means of annular wires t to two hoops r' and r^2 , the latter being larger than the former to permit the introduction of a circular carrier u , which is pivoted by means of a stem u' in a hole or socket in the top of the type-wheel spindle D .

10 The carrier may be made of a flat disk, as shown in Figs. 8 and 9, or may be formed with arms, as indicated by dotted lines in Fig. 9, and by fitting the stem u' loosely in its socket upon the spindle D the ribbon is moved but 15 slightly when the type-wheel is turned in its various positions.

Different portions of the ribbon are thus continually presented to the impression of the type, and as the varying size of the hoops r' and r^2 permits the ribbon to be lifted freely from the carrier, another ribbon may be substituted therefor without hinderance or delay whenever required.

The ribbon is made wide enough to cover 25 the whole face of the type-wheel, so as to operate with any number of rows of letters that may be formed thereon.

The means for raising and lowering the type-wheel to operate with two rows of letters 30 is not shown in the drawings, as it forms no part of the present invention and would obscure the illustration of the bell in Fig. 3.

A ribbon-guard i is affixed to the carriage-guide a , and consists in a thin leaf-spring 35 projected upward between the ribbon and the roll d , (see Figs. 2 and 3,) and is provided with a hole m , which coincides with the type in operation.

In Fig. 3 a pinion n upon the spindle D is 40 shown meshing with a segment n' , attached to a lever n^2 , by which the type-wheel is rotated.

Above the pinion is a toothed register-wheel N , and an acute tooth N' is formed upon the 45 vibrating frame g and penetrates at each vibration of the frame between two teeth of the register-wheel and operates to set the type-wheel with the type exactly opposite the opening m .

50 The ribbon-guard is formed with a slot, as shown in Fig. 2, to permit the penetration of the tooth N' .

A bell I is affixed to a post I' upon the bed B , adjacent to the type-wheel, and a hammer 55 o is hung from the bent top of the post by a lever-arm o' . A tappet o^2 is affixed to the right-hand end of the carriage b at such level as to strike the arm o' near its fulcrum when the carriage is nearly to the left-hand end of 60 its stroke, and thus throws the hammer violently against the bell.

The carriage b in such machines is commonly provided with a rack-bar v , which is shown formed as a flange projected backward 65 from the top edge of the carriage above the slot b' . This rack is shown in dotted lines in Fig. 1 of the drawings, and a pawl v' (shown

in Figs. 1 and 3) is pivoted upon a stationary post v^2 , Fig. 3, to feed the carriage one tooth at each vibration. The feeder-guides l' are 70 formed as leaf-springs applied to the flange v and bent backward from the same with a loop l , from the top of which loop the spring is bent under the feed-roll d and around the front side of the same.

75 By forming the spring with loop l great flexibility is given to that part which is under the roll and which embraces the front side of the same. The paper is inserted from the rear side of the roll over the loop l , and is 80 pushed between the guide and the roll, as indicated by the dotted line d^4 in Fig. 3. The spring holds the paper in such contact with the roll (which would be made of india-rubber or analogous material) that the paper is 85 fed as efficiently as between two rollers.

The stationary guide shown at the right-hand end of the feed-roll is shown in section 90 in Fig. 14, and is secured by rivet l^2 to the flange v .

95 The movable guide shown adjacent to the carriage-guide a in Fig. 2 is formed with a foot l^3 , which is extended from the flange downward over the front side of the carriage b .

A washer l^4 is applied over the foot, and a screw w is passed through the washer and through the slot b' into a gib w' upon the rear side of the slot, by which the feeder-guide 100 may be clamped in any desired position upon the carriage.

105 By the application of the foot l^3 to the slot, as described, the foot operates as a stop to set the carriage at the beginning of each line by contact with the carriage-guide a , as shown in Fig. 2, and thus obviates the need of any special stop for such purpose.

Having thus set forth the nature of my invention, what I claim herein is—

1. In a type-writer, the combination, with a 110 type-wheel, of an annular ribbon inclosing the periphery of the type-wheel, as and for the purpose set forth.

2. In a type-writer, the combination, with a 115 type-wheel, of a circular carrier fixed upon the top of the wheel and an annular ribbon suspended therefrom and inclosing the periphery of the wheel, substantially as herein set forth.

3. In a type writer, the combination, with a 120 type-wheel, of a circular carrier pivoted upon the top of the type-wheel to turn freely thereon, and an annular ribbon suspended therefrom and inclosing the periphery of the type-wheel, as and for the purpose set forth.

125 4. In a type-writer, the combination, with the type-wheel, of a circular carrier pivoted to turn freely upon the top of the same, and an annular ribbon secured at its edges to two hoops and fitted removably upon such carrier, as and for the purpose set forth.

130 5. In a type-writer, the combination, with a type-wheel and a frame vibrating to and from the same, of a feeding-carriage movable upon

the frame and the elastic-ribbon guard affixed to the frame to vibrate therewith and provided with an aperture coincident with the type in the printing operation, as and for the 5 purpose set forth.

6. In a type-writer, the combination, with the type-wheel, the vibrating frame, and the feeding-carriage movable thereon, of the bell mounted upon the frame of the machine adjacent to the type-wheel, the hammer o , suspended by lever-arm o' , and the tappet o'' upon the feeding-carriage, arranged to strike the lever-arm, substantially as herein set forth.

15 7. In a type-writer having a type-wheel and vibrating frame with feeder-carriage movable thereon, the combination, with the feeder-carriage having a flange v at the top and a feed-roll d rotated above such flange, of a feeder- 20 guide spring applied to the flange and bent around the front side of the feed-roll, as and for the purpose set forth.

8. In a type-writer having a type wheel and vibrating frame with feeder-carriage movable 25 thereon, the combination, with the feeder-car-

riage having a flange v at the top and a feed-roll d rotated above such flange, of a feeder-guide consisting in a spring applied to such flange and formed with the loop l and extension l' bent around the front side of the feed- 30 roll, as and for the purpose set forth.

9. In a type-writer having a type-wheel and vibrating frame with feeder-carriage movable thereon, the combination, with the feeder-carriage, with the vibrating frame having the 35 carriage-guide a near its middle, of the carriage b , carrying feed-roll d and provided with slot b' , and the feeder-guide l' , bent around the front side of the feed-roll, with foot secured over the slot by screw and gib, and operating as a stop to the stroke of the carriage, 40 substantially as herein set forth.

In testimony whereof I have hereunto set my hand in the presence of two subscribing witnesses.
